UNITED STATES PATENT OFFICE.

LUCIUS H. PRINDLE, OF NEW BRITAIN, CONNECTICUT, ASSIGNOR TO THE NORTH & JUDD MANUFACTURING COMPANY, OF SAME PLACE.

DESIGN FOR A BODY FOR SNAP-HOOKS.

SPECIFICATION forming part of Design No. 27,752, dated October 19, 1897.

Application filed August 10, 1897. Serial No. 647,755. Term of patent 14 years.

To all whom it may concern:

Be it known that I, LUCIUS H. PRINDLE, a citizen of the United States, residing at New Britain, Hartford county, Connecticut, have 5 invented certain new and useful Improvements in a Design for the Body of a Snap-Hook, of which the following is a full, clear, and exact description.

My design is illustrated by the accompanying drawings, in which—

Figure 1 is a perspective view. Fig. 2 is a rear elevation.

The leading features of my design are, first, the hooked front end A; second, the looped 15 rear end B; third, a diamond-shaped object C on the side of the loop B at the point where the hooked-shaped front end A joins said loop B, two of the side lines of the diamond-shaped object merging into the base of the hooked-

shaped end A, as shown, so as to destroy the 20 effect of a perfect diamond, the identity of the diamond-shaped object, as a whole, however, remaining; fourth, the provision of a diamond-shaped object C' on the rear side of the loop portion as well as on the front side of 25 the loop portion, and arranged as indicated above.

What I claim is—

The design for the body of a snap-hook, as herein shown and described.

Signed at New Britain, in the county of Hartford and State of Connecticut, this 7th day of August, 1897.

LUCIUS H. PRINDLE.
